UNITED STATES PATENT OFFICE.

RAYMOND P. PACKARD, OF TACOMA, WASHINGTON.

SALES-SLIP.

1,401,812.

Specification of Letters Patent. Patented Dec. 27, 1921.

Application filed March 3, 1921. Serial No. 449,282.

To all whom it may concern:

Be it known that I, RAYMOND P. PACKARD, a citizen of the United States, and a resident of Tacoma, in the county of Pierce 5 and State of Washington, have invented a new and Improved Sales-Slip, of which the following is a full, clear, and exact description.

This invention relates to improvements in 10 sales slips, an object of the invention being to provide a sales slip which is primarily designed to facilitate the tabulation upon an adding machine of the prices of articles which have been purchased and listed on 15 the slip. It is customary in retail stores, particularly grocery stores and the like to write out upon a slip a list of the articles purchased by a customer, together with the price of each article, and to mentally add 20 up the total cost of the purchases. It is inconvenient to make this calculation on an adding machine since when the slips are inserted in an adding machine and moved between the rollers to a point where the 25 name of the article purchased is visible and the machine operated to print the price of such articles upon the slip, the price will appear on one edge of the slip at a considerable distance below the space in which 30 the name of the article is written adjacent the other edge of the slip.

An object of this invention, therefore, is to overcome this difficulty by providing a slip having spaces so arranged thereon that 35 an adding machine may be conveniently used to tabulate the price of the articles purchased, and the price of each article will appear in the same space as the name of the article.

40 It is customary for storekeepers to make duplicates of sales slips and to use them as a basis for their bookkeeping, and the advantages to be derived by providing a slip, which may be used in an adding machine 45 will readily be appreciated.

With the above mentioned and other objects in view, the invention consists in certain novel features of construction and combinations and arrangements of parts as will 50 be more fully hereinafter described and pointed out in the claims.

In the accompanying drawings:

Figure 1 is a face view of my improved sales slip; and

Fig. 2 is a similar view illustrating a 55 slightly modified form of slip.

Referring in detail to Fig. 1 of the drawings, A represents my improved sales slip, which may have displayed thereon adjacent its upper edge, the name of the particular 60 firm using the slip, as indicated at 5. The main body portion of the slip is provided with a plurality of parallel staggered lines 6. These lines adjacent the left hand edge of the slip are parallel to the upper and 65 lower edges thereof and decline sharply from left to right at their intermediate portions, as indicated at 7. Adjacent their right hand ends, the lines again extend in parallelism with the upper and lower edges 70 of the slip. The right hand end of each line is preferably in the same horizontal plane as the left hand end of the line below it.

This arrangement of lines provides a 75 plurality of staggered spaces extending across the slip. Upon the left hand end of the upper line 6, the caption "Account For- 80 warded" may be displayed and upon the left hand ends of the three lowest lines 6, the captions "Paid on Account," "Balance Due" and "Proof" may be respectively displayed. The left hand ends of the spaces provide convenient places for writing the 85 names and prices of the articles purchased, as indicated at 8.

In use, after the names of the articles purchased have been written upon the slip and also the prices of such articles, the slip is inserted between the rollers of an adding 90 machine and when the caption "Account Forwarded" becomes visible, the machine is 95 operated to print the amount forwarded, as indicated at 9, adjacent the right hand edge of the slip. Due to the staggered for- 100 mation of the upper line 6, this amount will appear on the same line as the caption. In like manner, the printed prices of the articles purchased will appear at 10 upon the same line as the names and written prices 105 of the articles. The amounts may be quickly totaled upon the machine and the total printed upon the slip, as indicated at 11. The amount paid on account is indicated in its proper space. By mental subtraction, the amount due may be struck off the machine and these last two sums added on the machine to prove the account.

In Fig. 2, I have illustrated a slight modification, wherein a slip 3 is provided which also has a plurality of parallel staggered lines 15 thereon. These lines extend across 5 the slip in parallelism with the upper and lower edges thereof with the exception of an upwardly offset portion such as 16 in the intermediate portion of each line. This form of slip serves the same purpose as the 10 slip A, but in this instance, the penciled price of the article purchased appears at 17 on the offset portion of the lines 16, serving as a guide to one tabulating the price of the articles purchased upon an adding 15 machine.

In this form of slip, the initials P. A., standing for "Paid on Account," the initials B. D., designating "Balance Due," the initial P., for "Proof" and the initials A. 20 F. for "Account Forwarded," are displayed on the offset portions of the lines upon which these amounts are to be printed.

The numeral 17 and the initials serve as a guide when the slip is introduced into an 25 adding machine in the same manner that the indicia 8 and the captions on the slip A, serve as a guide when this slip is introduced into a machine.

Various slight changes and alterations 30 might be made in the general form and arrangement of the parts described without

departing from the invention and hence I do not wish to limit myself to the precise details set forth, but shall consider myself at liberty to make such slight changes and 35 alterations as fairly fall within the spirit and scope of the appended claims.

I claim.

1. A sales slip ruled to provide a plurality of parallel staggered lines, each of 40 said lines including an offset portion whereon the price of an article is listed and another portion whereon the price of said article is copied by a machine.

2. A sales slip for use in tabulating 45 machines, said slip being provided with designated spaces in which the price of articles are listed by hand, and being provided with designated spaces offset from and associated with said first-mentioned spaces wherein the 50 price of said articles is printed by a machine.

3. A sales slip for use in tabulating machines being provided with designated spaces within which data to be copied is 55 listed and having designated spaces associated with the first mentioned spaces wherein a copy of said data is made, said second-mentioned spaces being offset from said first-mentioned spaces.

RAYMOND P. PACKARD.
